JAMES LLOYD CASSADY, OF GENEVA, OHIO, ASSIGNOR TO THE AMERICAN FORK & HOE COMPANY, OF CLEVELAND, OHIO, A CORPORATION OF OHIO

TUBE AND ROD FORMING MACHINE

Application filed August 16, 1929. Serial No. 386,441.

This invention relates to methods and means for drawing or forming rods or tubes by means of roller dies, such as ball dies, and relates especially to such drawing or forming 5 wherein the rod or tube is drawn to different diameters in different portions of its length or to a continuously varying diameter throughout its length.

One of the objects of this invention is to 10 provide a method and means for drawing or forming tubes or rods whereby the effective diameter of the die-pass may be varied during the relative longitudinal movement between the die and the work and according to a pre-determined rate and type of variation.

Another object is to provide a machine and 15 method for drawing or forming tubes or rods to give to the tube or rod a transverse section which is of different size at different parts 20 of the rod or tube, longitudinally considered, and which cross-section may vary in size uniformly from end to end of the tube or rod, or may vary non-uniformly.

Another object is to provide a method and 25 means for redrawing or forming a thin-walled tube to change its form by the action of a roller die and in such a manner as not to fracture or otherwise unduly weaken the walls of the tube during the process.

Another object is to provide a method and 30 means for redrawing or otherwise operating upon tubes of a given diameter and wall thickness to vary the diameter and/or wall thickness throughout the length of the thin-walled tube or at certain portions thereof and 35 in such a manner that the resulting exterior surface of the tube will be relatively smooth throughout its length.

Another object is to provide a method and 40 means for redrawing or forming steel tubes of relatively high carbon content and to a predetermined generally tapering form and to such a predetermined wall thickness as to 45 render them applicable for use as the shafts of golf clubs.

Another object is to provide a method and 50 means for redrawing or forming tubes or rods of a given form to a tube or rod of a predetermined form differing therefrom and with efficiency and economy.

Another object is to provide a method and means for redrawing or forming from a substantially non-tapering tube a relatively strong, highly resilient tapering tube having any predetermined desired wall thickness and 55 diameter at different portions of its length.

Another object is to provide a method and means for drawing or forming rods or tubes in which, during the operation on the rod or tube, scoring thereof is prevented.

Another object is to provide, in a machine for drawing or forming tubes or rods of considerable length in proportion to their diameters, and in which the work is rapidly rotated, an improved means for supporting 65 the work to prevent whipping thereof.

Another object is to provide in a machine for drawing or forming tubes or rods of considerable length in proportion to their diameter, and in which the work is rapidly 70 rotated, an improved means for supporting the work while being operated upon.

Another object is to provide, in a machine for drawing or forming tubes or rods in which the work is gripped in a chuck or the like, an improved means for removing or 75 withdrawing the finished work from the chuck or the like.

Another object is to provide, in a machine for drawing or forming rods or tubes or the like, an improved die of the roller or ball type.

Another object is to provide in a machine for drawing or forming rods or tubes or the like an improved die having a die pass of the 85 roller or ball type through which the rod or tube may be drawn at a relatively slow rate to draw or form it to a smooth surface and the die pass of which may be relieved to permit the rod or tube to be withdrawn through the die pass at a high rate or with a "quick return" movement without disfiguring the surface.

Other objects of my invention and the invention itself will become apparent from the following description of an embodiment thereof taken in connection with the accompanying drawings, in which:

Fig. 1 is a side elevational view of the 100

machine embodying my invention with portions thereof broken away;

Fig. 2 is a top plan view of the machine of Fig. 1;

Fig. 3 is an end elevational view of the machine of Fig. 1 taken from the left end thereof.

Fig. 4 is an end elevational view of the machine of Fig. 1 taken from the right end thereof;

Fig. 5 is a view taken from the plane 5 of Fig. 1 and to an enlarged scale and with some of the parts omitted for simplicity;

Fig. 6 is a sectional view taken approximately from the plane 6 of Fig. 2 and showing parts of a ball die forming part of a ball type drawing or forming die constituting part of my invention;

Fig. 7 is a view taken approximately from the plane 7 of Figs. 5 and 8;

Fig. 8 is a view taken approximately from the plane 8 of Figs. 7 and 5;

Fig. 9 is an enlarged view of a portion of the die shown in Fig. 8 with a portion thereof broken away;

Fig. 10 is a vertical sectional view of a work support forming part of my invention and shown in elevation and to a smaller scale, as in Fig. 1;

Fig. 11 is a sectional view of a tube to be formed or drawn by the machine of my invention and with a tapering mandrel therein;

Fig. 12 is a view of the tube and mandrel of Fig. 11, showing the tube in the process of being formed;

Fig. 13 is a sectional view taken approximately from the plane 13 of Fig. 1, showing a work support forming part of my invention and drawn to a larger scale;

Fig. 14 is a view similar to Fig. 13 with some of the parts thereof in different positions;

Fig. 15 is a perspective view of a stop shown also in Figs. 13 and 14, but drawn to a larger scale;

Fig. 16 is a fragmentary view of one of the parts of Figs. 13 and 14, but drawn to a larger scale;

Fig. 17 is a view taken from the plane 17 of Fig. 16;

Fig. 18 is a perspective view of a wedge adapted to operate parts shown in Figs. 13 and 14.

Referring to the drawings, I have shown at 1 the main frame or bed of the machine embodied in my invention resting upon the supports 2 and 3. The support 3 houses a motor 4, which, in a manner to be described, supplies power to draw the tube or rod to be formed through the forming die. The motor 4 is connected by a belt 5 to a pulley 6, having rotative bearing supports in a housing 7 on the bed 1. By means of a shaft 8, a worm 9 and worm gear 10, spur gears 11

and 12 and a vertical shaft 13, the pulley 6 drives a sprocket wheel 14. All of the driving connections, just mentioned, exclusive of the sprocket, are generally enclosed in the housing 7, stationarily supported on the bed 1. A sprocket chain 15 meshed with the sprocket wheel 14 extends the full length of the machine bed, and passes over an idler sprocket 16 mounted in a housing 17 and supported by a bracket 18 and adapted to rotate on a vertical axis. One free end of the chain 15 is connected at 19 to a chuck carriage 20 adapted to move back and forth longitudinally on the bed of the machine, in a manner to be described; and the chain starting from the connection at 19 passes to the left, as viewed in Fig. 2, over the sprocket wheel 14 and thence to the right over the idler sprocket 16, and thence to the left and is again connected to the carriage 20 at 21. By this means, the motor 4 when energized may draw the carriage 20, say, to the left, as viewed in Figs. 1 and 2, to draw or pull the work through the die, to be described, and upon reversing the motor 4, in any convenient manner, the chain will pull the carriage 20 in the opposite direction for a second operation.

The chuck carriage 20, above referred to, comprises a main slide 22 reciprocatively supported in ways 23 on the bed 1 of the machine. Upon the slide 22 are mounted a motor bracket 24, a motor 24' thereon, belted by belts 26 to a pulley 27 rotatably supported on the slide and drivingly connected to a rotatable work gripping chuck 28. These parts may be constructed in any known or suitable manner and the detail parts thereof form no part of my present invention. By means of start and stop switch push buttons 29, the motor 24' may be controlled to conveniently start and stop the rotation of the chuck 28, and the motor 24', being mounted on the slide 22, is movable therewith and thus conveniently supplies power to the chuck 28 while the carriage 20 is moving longitudinally on the ways, as above described.

Indicated generally at 30 is a die mounted stationarily upon the bed 1. As indicated in Figs. 1 and 2, a work piece 31, such as a tube or rod to be drawn or formed, may be gripped in the chuck 28 and extend entirely through the die 30 and be supported on its free end by a work support 32.

As will now be more fully set forth, when the carriage 20 is propelled along the ways toward the left, Figs. 1 and 2, to draw the work 31 through the die 30 to operate upon it, the work support 32 will move concurrently and in unison with the carriage 20 to support the free end of the work while the drawing or forming operation is going on; and when the chuck 28 has moved to the left sufficiently far to leave a relatively long unsupported length of the work piece 31 between

the chuck 28 and the die 30, to cause the rapidly rotating work 31 to have a tendency to whip, a work support or steady rest 33 automatically comes into position and engages 5 opposite sides of the work 31 to steady it and prevent whipping.

The die 30 comprises a housing 34 bolted to the bed 1, as shown in Fig. 5, by bolts 35. The housing 34 is bored out as at 36, and the 10 bore is sealed at one end by a head 37, and at the other end by a head 38 and contains the die or die-pass mechanism.

The head 37 is bolted to the housing 34 by bolts 39. The head 38 is removably secured 15 to the housing; for this purpose the housing is provided with a pair of longitudinally extending brackets 40 bolted thereto terminating in inwardly directed hooks 41—41; upon the head 38 is bolted as at 42 a pair of 20 cams 43 having cam faces 44; the head 38 is also provided with a handle 45 and with an annular shoulder 46 fitting the bore 36 of the housing. By this construction, the head 38 may be rotated on the axis of the housing 25 bore by the handle 45 either in one direction to engage the cam faces 44 with the hooks 41 to clamp the head 38 to the housing 34 and thus secure it on the housing, or in the other direction to disengage the cams and hooks 30 and permit the head 38 to be removed from the housing or loosened therein.

Mounted at one side of the axis of the bore 36 and rotatable in bearings 46 and 47 is a worm assembly comprising a sprocket wheel 35 48 adapted to mesh with and be rotatably driven by one line of the double sprocket chain 15 as the latter moves longitudinally on the bed of the machine; a clutch hub 49 secured to the sprocket 48 and provided with 40 clutch teeth 50; a worm 51 provided on its lower end, as viewed in Fig. 6 with a second set of clutch teeth 52 engaged with the teeth 50; and provided on its upper end with a hub 53 terminating outwardly in an adjusting 45 head 54, the head having a flange 55 resting on the upper side of the housing 34. The parts thus described are all bolted together by a through bolt 56 having a head 57 and a threaded portion 60 screwed into a nut 59 on 50 the adjusting head 54.

To adjust the worm 51 rotatively with respect to the sprocket 48, the nut 54 may be loosened to render the clutch teeth 50 and 52 disengageable and then the worm may be 55 turned independently of the sprocket by turning the hub 53, which is secured to the worm. To turn the hub, a suitable bar may be inserted in a radially disposed hole 58 in the flange 55 of the hub. After such adjustment, the nut 54 may again be tightened to re-engage the clutch teeth 50 and 52 to rigidly maintain the relative rotative positions of the sprocket and worm.

Within the casing 34 and fitting the bore 36 is a ram 61 adapted to be reciprocated in

the bore by the following means. The ram, which is generally cylindrical, has a portion of reduced diameter 62 upon which is rotatably mounted a hollow cylindrical cam element 63, substantially fitting the bore 36, 70 provided with a plurality, preferably two, generally helically arranged cam grooves 64. Studs 65 are screwed into the ram along radial lines and their free externally projected body portions carry the inner races of ball bearings 66, the outer races of which engage the walls of the cam grooves 64. Between the head 67 of the studs and the external cylindrical surface of the cam element 63 are mounted guides 68 adapted to move 75 axially of the bore in guide-ways 69. It will now be apparent that if the cam element 63 be rotated in the bore, the cam grooves will propel the ball bearings 66, the studs 65 and therefore the ram 61 axially of the bore 63, 80 and that the guide 68 will prevent concurrent rotation of the ram in the bore.

To rotate the cam 63 in this manner, it is provided with a worm wheel 70, secured thereto by bolts 71, the teeth of the worm wheel being in meshed engagement with the hereinbefore described worm 51. The end-wise thrust, due to the reaction of the cam 63 upon the ram 61 when the latter is propelled toward the left, Figs. 6, 7 and 8, is 85 taken up by an end thrust ball bearing 72 between the worm wheel and the inner face of the end plate 37.

To absorb the relatively light thrust in the opposite direction and to hold the worm wheel and cam normally stationary axially, a bushing 73, provided with a flange 74 seated in a corresponding recess of the worm wheel 70, is mounted axially in the end plate 37; and by means of a shoulder 74' on the bushing and a nut 75, the bushing is rigidly secured in the end plate. The bushing is also provided with an axial bore 76, for a purpose to be described.

In the left end of the ram 61, as viewed in Figs. 6, 7 and 8, is a die annulus 77 bored out along its axis to outwardly divergent conical form and supported on its external periphery by a ball bearing 78 seated in a suitable recess in the ram 61. The internal end of the annulus 77 abuts upon an end thrust ball bearing 79 also seated in a suitable recess in the ram. A plate 80, secured by screws on the end of the ram, holds the annulus 77 and ball bearing 78 in place.

Within the ram and along its axis and disposed axially therewith is a ball supporting tube 81, anchored against rotation within the ram by a key 160 disposed in a radial slot in the ram and projecting into a key-way 161 in the tube 81. Said tube 81 is provided at its left end, as viewed in Figs. 6, 7 and 8 and particularly as shown in Fig. 9, with a plurality of ball recesses 82. These recesses are generally cylindrical along radial lines and adjacent the end of the tube 120

- so that the cylindrical recesses are open at one side, as at 83. The ball supporting tube itself has an axial bore 84 and the recesses 82 terminate internally at this bore. Preferably, as at 84, the inner ends of these recesses are restricted at one side thereof by a small projecting shoulder 84'. Steel balls 85 are placed in the recesses and are trapped therein by the recesses, by the shoulders 84'.
 10 and by the conical bore of the die annulus 77, which projects over the balls. The balls when in the recess project beyond the extreme left end of the tube 81.
- From the foregoing description, it will be seen that by movement of the ram toward the left in Figs. 6, 7 and 8, the conical bore of the annulus 77 will force the balls 85 inwardly radially in their recesses.
 15 In the end plate 38 a ball thrust construction is provided comprising a nose piece 86 having a bore 94 co-axial with the bores 84 and 76, above referred to, and having a planular face at right angles to the bore adapted to engage all of the balls 85. The nose piece 86 is mounted in the end of a threaded tube 87 upon which is screwed a flanged nut 88 and a lock nut 89 therefor. The flange of the nut 88 rests upon an end thrust ball bearing 90 mounted in a suitable recess in the end plate 38. A plate 91 secured to the end plate by suitable screws holds the ball bearing 90 in its recess. By means of the nut 88 and lock nut 89, the tube 87 and therefore the nose piece 86 may be adjusted axially in the head 38 to vary the position of the nose piece 86 with respect to the balls 85; and to give access to these parts, the head 38 is made easily removable, as hereinbefore described.
 20 The operation of the die, above described, is as follows: A mandrel, such as the mandrel 95 of Figs. 11 and 12, is secured to the chuck supporting carriage 20 co-axial with the gripping chuck 28 and passes axially through the die by way of the aligned axial bores 94, 84 and 76 and is rotatable with the chuck 28. The means by which the mandrel is secured to the chuck is not essential to my invention and is not shown; preferably, however, it is permanently fastened to the carriage or chuck at its large end by a suitable gripping means independent of the tube gripping means, or may be screw threaded into the inner end or base of chuck; the tube 25 is gripped upon the mandrel by the chuck jaws outwardly of the point at which the mandrel is secured. The mandrel is left permanently in the chuck and successive tubes telescoped theron and removed therefrom in the operation of the machine. The mandrel is shaped to conform to the inner wall of the tube to be formed. The tube 31 to be worked upon is then telescoped over the free end of the mandrel, through the bores 76, 84 and 94, respectively, and on into the chuck 30

28 and is gripped thereby to rotate therewith. The balls 85 of the die surround the tube. The motor 25 is started and rapidly rotates the mandrel and tube. The motor 4 is then started, which causes the chain 15 to travel and to pull the carriage 20 along the bed of the machine toward the left, in Figs. 1 and 2, and thus to pull the mandrel and tube through the die.
 35

The movement of the chain meshed with the sprocket 48, Fig. 8, turns the sprocket and the worm 51 and the worm wheel 70 and in consequence turns the cam 63 of the die, Figs. 6, 7 and 8, and propels the ram 61 toward the left. The ram 61 is thus moved concurrently with the movement of the tube and mandrel through the die, the movement of the ram being much slower than that of the tube and mandrel. The movement of the ram brings the die annulus 77 into engagement with the outer surfaces of the balls 85 and gradually forces them inwardly, first, into engagement with the outer wall of the tube 31 and thereafter gradually farther and farther inwardly toward the axis of the tube. The tube, meanwhile, rapidly rotating and being drawn through the circle of balls is rolled or forged or formed by the balls to a smaller and smaller diameter and is forced or forged inwardly upon the mandrel 95.
 40

Thus, not only is the outer diameter of the tube changed, but the inner diameter is changed and the diameter of the mandrel may be selected to cause the wall of the tube to have any pre-selected thickness. Furthermore, for any given mandrel or predetermined internal diameter of the tube being formed, the external diameter of the tube and also, therefore, the thickness of the wall of the tube may be varied, as desired, by changing the shape of the cam grooves 64 to vary the axial feed of the ram 61.
 45

Thus, by choosing a suitable mandrel 95 and a suitable cam 63, the tube may be forged or formed to have any pre-selected wall thickness and internal and outside diameter; and, as will be understood, the taper of the tube may be uniform from end to end or may vary at different portions longitudinally, and the taper may be all in one direction or part of it may be in the reverse direction, i. e., the tube may be tapered so as to become smaller in one direction and then larger in the same direction. It will also be understood that the wall thickness may be controlled independently of the taper, inasmuch as the internal diameter of the tube may be determined by the diameter of the mandrel therein and the external diameter of the tube may be determined by the rate of feed of the ram 61 relative to the rate at which the tube is drawn through the die.
 50

During the forming or forging of the tube by the rolling of the balls, as above described, the rotating tube will rotate the balls and the

balls will rotate the die annulus 77 on its ball bearings 78 and 79. Furthermore, the balls will rotate the nose piece 86 on the ball bearing 90 supporting it. The combined action of the balls in rolling upon the planular face of the nose piece 86 and the conical bore of the annulus 77 causes the balls to constantly present new points of contact to the tube being formed, resulting in a smooth surface on the tube and a uniform wear on the balls and insuring the continuation of their rolling movement. The exact position of the ram 61 axially with respect to the rod and therefore the exact point on the rod, at which a given diameter will be formed by the balls 85, may be determined by rotating the cam independently of the longitudinal movement of the tube through the die and this in turn may be effected by turning the worm 51 adjustably independently of the sprocket 48 in the manner hereinbefore described.

During the drawing operation, the balls and other parts may be thoroughly lubricated by a flow of oil supplied to the interior of the casing 34 through a suitable connection 97 by an oil pump 98. The means for supporting the free end of the tube and mandrel at the beginning of the drawing operation will now be described.

Projecting from the right end of the bed, as viewed in Figs. 1 and 2, is a pair of ways 98, preferably of circular cross-section, as shown in Fig. 4. Mounted for reciprocating movement on the ways 98 is a carriage 99, provided with laterally extending arms 100-100 and provided with a grooved way 101 extending therethrough in the longitudinal direction of the machine. Resting on the arms 100 are the free ends of draw bars 102-102, the extreme other ends of which terminate in clevises 103-103 pivotally connected to the carriage 20.

The draw bars 102 have downwardly open forks 104-104 embracing the arms 100. When the carriage 20 is propelled along the bed, the draw bars 102 pull the carriage 99 along the ways 98 by means of the forks 104 and arms 100. When the carriage has thus been propelled toward the left, in Figs. 1 and 2, until it is adjacent the end of the bed, suitable lugs or projections 105 on the bars 102 ride upwardly upon pins 106 on the frame and the bars 102 are raised freeing the forks 104 from the arms 100 and stopping further propulsion of the carriage 99. In the way 101 of the carriage 99 is an auxiliary carriage 107, shown in cross-section in Fig. 10 and provided with an internal bore 108 co-axial with the bores hereinbefore referred to in the die. Within the bore is a tube 109 rotatably supported by ball bearings 110-110. The extreme outer end of the auxiliary carriage 107 is provided with a bracket 111 on which is a gripping plate

112 pivoted at 113 for rotation in a transverse plane, and concentric with the pivot 113, is provided with an arcuate slot 114. On the upper side of the carriage 107 is a stud 115 disposed in a slot 116 of a lever 117 arranged transversely with respect to the bed of the machine and pivoted at one end, as at 118, to the carriage 99. By this construction, the auxiliary carriage 107 may be reciprocated in the way 101 by moving the lever 117 to the right or left in Fig. 2.

In the operation of the machine, as above described, when the carriage 20 is in its extreme position toward the right, the mandrel and tube project out of the right end of the die housing 34 and through the tube 109 of the carriage 107 and are supported thereby. The movement of the carriage 20 toward the left, which draws the mandrel and tube toward the die also by means of the bars 102, draws the carriages 99 and 107 in unison therewith and thus during this part of the drawing operation, the carriage 107 continuously supports the free end of the rapidly rotating tube and mandrel to prevent whipping thereof.

At the end of the drawing operation, the carriage 20 may be returned toward the right with a rapid or high speed return and it may therefore be undesirable for the die-balls to be in rolling contact with the tube during this movement. To cause the tube to return without being rolled on the return stroke, the balls may be freed from the tube by relieving the pressure of the nose piece 86 on the balls and this in turn may be effected by rotating the head 38 slightly to relieve the cam pressure thereon.

At the end of the drawing operation, and when the carriage 20 is returned toward the right, the forks 104 will pick up the arms 100, and the carriages 99 and 107 are thereby likewise returned toward the right to their original position. The forming or forging of the tube is preferably stopped adjacent the end thereof leaving an unformed portion, as at 119, Fig. 12, and a shoulder 120 between the unformed portion and the formed portion. When the auxiliary carriage 107 is in its returned position, this shoulder 120 will lie adjacent to the gripping plate 112 on the carriage. This plate may then be manually rocked toward the tube causing the curved groove 114 therein to pass over the tube at the shoulder. Thereupon, the lever 117 may be moved to the right, Fig. 2, and this will cause the gripping plate 112 by means of its slot to engage the shoulder 120 of the tube and forcibly strip the tube from the mandrel, after suitably releasing the chuck 28. The plate 112 may then be rocked back out of the way and the formed tube removed from the machine.

During the drawing or forming of the tube,

after the chuck 28 has been moved a considerable distance from the die, the rapidly rotating tube and mandrel may whip between the chuck and the die and to prevent this, 5 the following means, hereinbefore referred to, is provided.

Mounted rotatably in and transversely of the bed 1 of the machine is a tube or hollow shaft 125, Figs. 1, 13 and 14. The hubs 126—10 126 of a pair of arms 127 are slidably mounted on the tube 125. The longitudinal sliding movement of the hubs is limited by means of pins 128 passing diametrically through the hubs and tube and embraced by slots 129 in 15 the tube. The pins also adapt the arms and the tube to be revolved in unison around the axis of the tube. The tube is prevented from axial movement in the frame by a collar 130 on one end and a collar 131 on the other end 20 secured to the tube, the latter collar being provided with a downwardly extending arm 132, for a purpose to be described.

Short rods 133 project into the tube from each end and the aforesaid pins 128 pass 25 through holes in the rods. By means of flat springs 134—134 resting at their outer free ends upon the rods 133 and being secured at their other ends to the bed of the machine, as at 135 Fig. 1 are provided to normally resiliently press the rods toward the middle of the tube and thus normally resiliently press the hubs 126 and arms 127 toward each other. Furthermore, by means of the arm 132, the tube 125 may be rotated on its 30 axis and the movement of the tube may be transmitted through the walls of the slots 129 to the pins 128 and to the arms 127 to rotate the arms around said axis. Normally, by means of a tension spring 136, the arms 35 127 are resiliently constrained to turn in the counter-clockwise direction, as viewed in Fig. 1, or away from the observer, as viewed in Figs. 13 and 14.

Loosely mounted on the tube 125 at its 40 middle is a dog 137, shown separately in Fig. 15, within which the tube 125 may rotate and which is itself prevented from rotation by means of two lugs 138—138 extending downwardly therefrom and straddling a web 139 45 on the bed 1, the angular or rotative position of the dog around the tube 125 being adjustable by means of studs screwed into threaded holes 140—140 in the lugs 138 and the inner ends of the studs engaging the web 139, one of 50 55 which studs 141 is shown in Fig. 14. The dog 137 has four stop faces 142 all substantially in a vertical plane through the axis of the tube 125. The hubs 126 have each a pair of stop faces 143—143, shown separately in 60 65 Figs. 16 and 17 adapted to coincide with the faces 142.

When the hubs 126 by a means to be described, are moved away from each other on the tube 125 to the extent permitted by the 65 slots 29, i. e. from the position shown in Fig.

13 to that shown in Fig. 14, the stop faces 143 on the hubs will be moved out of engagement with the stop faces 142 on the dog (and conversely when the hubs are moved in the opposite direction) and the hubs and arms may be rotated from the vertical position shown in Figs. 13 and 14 to a position below the ways 23 of the machine or to the dotted position shown at 144 in Fig. 1.

The means for spreading the arms apart 70 and rocking them out of their vertical position comprises a wedge 145 shown separately in Fig. 18 and indicated in dotted lines in Fig. 1. The wedge 145 is preferably constructed in the form of a plate horizontally 75 mounted on and movable with the carriage 20 and having on one end inclined cam surfaces 146—146. The position of the wedge 145 is such that upon movement thereof, toward the right in Fig. 1, the cam surfaces 146 engage lugs 147 on the opposing portions of the arms 127 and spread the arms 127 and hubs 126 apart to release them from the stop faces, as above described. Further movement of the wedge 145 will bring shoulders 80 148 thereof into engagement with the arms 127 and rock the arms around out of the vertical, as described. Movement of the wedge in the other direction, to the left in Fig. 1, will remove the shoulders 148 from the arms 85 127 and retract the cam surfaces 146 from the lugs 147 permitting the springs 134 to press the hubs toward each other and therefore resiliently against the dog 137; and as the wedge 145 moves farther away, the spring 136 will rotate the tube 125 and the arms 127 until the stop faces 143 of the hubs 126 are 90 opposite the stop faces 142 of the dog, whereupon the hubs 126 will resiliently and suddenly move toward each other and be held in 95 a vertical position by the said stop faces.

The arms 127 are provided with steady rest jaws 150 provided with cylindrical gripping grooves 151. When the arms 127 are in their vertical position and resiliently held toward each other, as in Fig. 13, the grooves 151 grip the tube being operated on at opposite sides thereof to prevent its whipping.

The wedge 145 is so positioned on the carriage 20, so that in the movement of the carriage, the wedge permits the arms to move to their vertical position when the chuck 28 has been withdrawn to a convenient distance from the arms 127, as illustrated in Fig. 1.

My invention is not limited to drawing tubes to any particular shape. As stated hereinbefore, the machine is susceptible to modification and adjustment for drawing tubes to any predetermined variation of taper and/or variation of wall thickness. Furthermore, it will be understood that in connection with the modification of the cam groove 64 to vary the shape of the tube, the cam groove 64 may be so formed as to cause the resulting tube to be stepped instead of 100

tapered, i. e. composed of a series of successive smaller cylindrical portions; and as referred to hereinbefore, the taper may be in one direction on part of the tube and in the other direction at another part of the tube.

5 Also, inasmuch as the principles underlying my invention may be carried out by embodiments differing from that shown, my invention is not limited to the exact embodiment herein illustrated and described, and although my invention is illustrated and described as a tube drawing machine, it will be understood that in many aspects, it is applicable to the drawing of solid rods.

10 Furthermore, although I have shown and described my invention as applied to a machine in which the die mechanism remains stationary and the work is drawn therethrough, it will be understood that my invention may 15 be applied to the reverse type of machine in which the work is held stationary and the die is drawn over the work.

15 Applicant has copending herewith applications Serial No. 350,620, filed March 28, 20 1929, and Serial No. 350,621, filed March 28, 1929, in which claims are being prosecuted directed to subject matter disclosed in this patent.

I claim:

30 1. In a machine of the class described, a main supporting frame, a die head fixed on the frame, a die pass in the die through which work to be operated upon may be drawn, a work gripping head movable on the frame 35 relative to the die head adapted to grip the work and draw it through the die pass, a steady rest device adapted to engage the work between the gripping head and the die head and means for automatically moving the device into engagement with the work when the work head is at or beyond a predetermined 40 distance from the die head.

2. In a machine of the class described, a main supporting frame, a die head fixed on the frame, a die pass in the die through which work to be operated upon may be drawn, a work gripping head movable on the frame relative to the die head adapted to grip the work and draw it through the die pass, a 45 steady rest device adapted to engage the work between the gripping head and the die head and means for automatically moving the device into engagement with the work when the work head is at or beyond a predetermined 50 distance from the die head, and means for removing the steady rest from engagement with the work and when the work gripping head is nearer the die head than said predetermined distance.

55 3. In a machine of the class described, a main supporting frame, a stationary die head fixed on the frame provided with a die pass through which work may be drawn, a work head movable on the frame and adapted to grip the work and draw it through the die

pass, an anti-whipping device adapted to engage the work between the work head and die head, and means controlled by the movement of the work head for automatically bringing the steady rest into engagement with the work and automatically removing it therefrom when the work head is respectively beyond or within a predetermined distance from the die head.

4. In a machine of the class described, a main supporting frame, a die head fixed on the frame and provided with a die pass through which work may be drawn, a work head movable on the frame and adapted to grip the work to draw it through the die, the length of the die head in the direction of movement of the work head being proportioned to the length of the work to be drawn to permit the free end of the work to project out of the die head, a work support for the free end of the work movably mounted on the main frame and connections between the work support and the work head for propelling the work support on the frame in unison with the movement of the work head.

5. In a machine of the class described, a main supporting frame, a die head on the frame provided with a die pass through which work is adapted to be drawn, ways on the frame, a work head reciprocable on the ways and adapted to grip the work and draw it through the die, auxiliary ways on the frame, a work support on the auxiliary ways reciprocable thereon, detachable connections between the work head and the work support for moving the work support in unison with the work head and means on the frame for automatically disconnecting the work support from the work head at a predetermined point in the movement of the work support.

6. In a machine of the class described, a main supporting frame, a die head on the frame provided with a die pass through which the work is adapted to be drawn, a work head movable on the frame and adapted to grip one end of the work and draw it through the die, a work support movable on the frame for supporting the free end of the work, connections between the work head and the work support for moving them in unison, the work support comprising ways on the frame, a slide on the ways movable thereon, a supporting element on the slide upon which the work is adapted to rest and adapted to be moved on the slide in the direction of the work, two gripping means on the supporting element adapted to grip the tube and means for moving the supporting element on the slide to cause the gripping element to move the tube relative to the work head.

7. A main housing, a ball die pass in the housing comprising a plurality of balls enclosing an aperture through which work is adapted to be drawn, means for progressive-

ly and forcibly restricting the aperture enclosed by the balls at a rate commensurable with the rate of movement through the aperture, the force applied by said restricting means having a component in the direction of the axis of the aperture, and a thrust element for the balls resisting said axial component of force, said thrust element being supported by a wall of the housing and adjustable therein axially toward and from the aperture.

8. In a ball die comprising an enclosing housing and a ball die pass therein, a plurality of balls disposed in a circular pattern and enclosing an aperture therewithin, through which aperture work while rotating is adapted to be drawn, means for progressively restricting the aperture concurrently with the movement of the work therethrough to draw the work to tapered form, said means comprising an annulus surrounding the balls in engagement therewith on an internal conical bore of the annulus and means for moving the annulus axially with respect to the aperture, a radial ball bearing support and an axial thrust ball bearing for the annulus, an end axial thrust element for the balls having an aperture aligned with the aperture within the balls and having a planular face for engagement by the balls, supporting means for the element including a nut in which the element is screw threadedly axially adjustable, an end thrust ball bearing for the nut and a transverse head in the housing for the ball bearing.

9. In a ball die mechanism, a housing, a plurality of balls, a support for the balls adapted to support them disposed in a circular pattern and enclosing a die pass aperture therewithin, an end thrust element for taking up axial thrust of the balls, a transverse head on the housing for supporting the end thrust element, means for adjusting the position of the element axially relative to the head and means detachably connecting the head to the housing, said means comprising a rotary bearing for the head in the housing, a handle on the head for rotating it, and relatively stationary and movable wedging elements on the housing and head.

10. In a tube drawing machine comprising means for drawing a tube blank to a smaller diameter upon a mandrel therewithin and comprising means for gripping the mandrel independently of the tube and for stopping the diameter reducing drawing operation at a point adjacent an end of the blank to produce a shoulder thereon; stripping means for longitudinally stripping the tube from the mandrel comprising a stripping element movable into a position to engage the tube shoulder, and means for moving the engaged stripping element longitudinally of the mandrel to longitudinally strip the tube therefrom.

11. In a tube drawing machine comprising

means for drawing a tube blank upon a mandrel therewithin, and comprising a relatively movable tube and mandrel gripping head and a die, and comprising gripping means on the head for gripping the mandrel independently of the tube, and comprising means for stopping the drawing operation at a point adjacent an end of the blank to produce a shoulder thereon, and for reversing the drawing movement to project the shoulder end of the tube out of the die; stripping means for stripping the tube from the mandrel comprising a stripping element for engaging the tube shoulder and means for moving the engaged stripping element longitudinally of the mandrel to longitudinally strip the tube therefrom.

12. In connection with a machine for drawing a tube upon a mandrel therewithin and for gripping the mandrel independently of the tube, the method of stripping the tube from the mandrel at the end of the drawing operation which includes stopping the drawing operation at a point adjacent an end of the tube, then releasing the tube but retaining a grip upon the mandrel then engaging the tube at the shoulder produced at the end of the drawing operation by a stripping element and then moving the stripping element longitudinally of the mandrel.

13. A ball die comprising a casing, a series of balls within said casing, a raceway for said balls comprising bearing thrust elements on said casing at each side of the said series of balls and a ring having an inner longitudinally tapered wall encircling said balls with said tapered wall in engagement therewith, means associated with the ring to adjustably position it longitudinally of the die, said means comprising a cylindrical barrel on the casing disposed coaxially of the raceway and a pair of relatively rotatable cam elements disposed within the barrel, one of said cam elements being in the form of a cylindrical sleeve, the other in the form of a piston telescoped within the sleeve, the sleeve having a cut away portion in the wall thereof longitudinally inclined to a transverse plane disposed at right angles to the axis of the sleeve, said piston having a bearing portion projected radially therefrom into the space provided by the cutting away of the sleeve, one of said cam elements bearing against an end wall of the casing at one end portion thereof, the other cam element adapted to communicate a thrust effort to said ring by movement of an opposite end portion upon relative rotation of the cam elements, and means to effect a progressive relative rotational movement of the cam elements.

14. A ball die comprising a casing, a series of balls within said casing, a raceway for said balls comprising bearing thrust elements on said casing at each side of the said series of balls and a ring having an inner longitudinal-

ly tapered wall encircling said balls with said tapered wall in engagement therewith, a work support longitudinally spaced from the raceway and adapted to rotate the work projected 5 within the balls of the raceway, and means to effect relative longitudinal movement of the work support and casing, said casing comprising a cylindrical barrel disposed coaxially of the raceway and relatively rotatable cam 10 elements disposed within the barrel, one of said cam elements being in the form of a cylindrical sleeve, the other in the form of a piston telescoped within the sleeve, the sleeve having a cut away portion in the wall thereof 15 longitudinally inclined to a transverse plane at right angles to the axis of the sleeve, said piston having a bearing portion projected radially therefrom into the space provided by the cut away portion of the sleeve, one of said 20 cam elements bearing against an end wall of the casing at one end portion thereof, the other cam element adapted to communicate a thrust effort to said ring by movement of its opposite end portion upon relative rotation 25 of the cam elements to adjustably position the ring longitudinally of the die, and means to effect a progressive relative rotational movement of the cam elements, comprising a worm gear disposed in driving relation to one 30 of said elements and a driving worm for rotating said gear, and means to maintain rotational movement of said worm commensurable in rate with the relative longitudinal movement of the work support and the casing.

35 15. In a die for progressively varying the diameter of a rod or tube in definite longitudinal disposed portions thereof, a die head, comprising a tubular die holder, a sleeve telescoped within an end portion of the die holder, 40 a piston telescoped within the sleeve, said piston comprising an annulus telescoped within the cylindrical die holder, said annulus adapted to be thrust by said piston longitudinally of said head, means interlocking said piston 45 and sleeve, comprising a helically slotted portion of the sleeve and a radially projecting portion of the piston adapted to be received in the slotted portion, means to effect rotational movement of the sleeve, and means 50 restraining said piston from rotative movement relative to said head, and a contracting die comprising a series of die balls encircled by the annulus, the annulus having an inner wall of progressively 55 different diameter proceeding longitudinally thereof engageable with the balls, said piston and ring movable longitudinally together over said balls.

In testimony whereof I hereunto affix my
30 signature this 10th day of August, 1929.

JAMES LLOYD CASSADY.
